UNITED STATES PATENT OFFICE.

RASMUS CHRISTENSEN, OF OGDEN, UTAH.

MOP-WRINGER.

No. 826,087.

Specification of Letters Patent.

Patented July 17, 1906.

Application filed January 12, 1905. Serial No. 240,689.

To all whom it may concern:

Be it known that I, RASMUS CHRISTENSEN, a citizen of the United States, and a resident of Ogden, in the county of Weber and State 5 of Utah, have invented a new and Improved Mop-Wringer, of which the following is a full, clear, and exact description.

The object of the invention is to provide a new and improved mop-wringer which forms 10 a permanent fixture of a pail or like receptacle and is arranged to permit of conveniently placing a mop in the wringer to wring out the mop and to cause the dirty water to pass into the pail without splashing the water 15 upon the floor during the wringing operation.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a perspective view of the improvement, showing one of the wringer-rolls in an open position. Fig. 2 is a sectional side elevation of the same on the line 2 2 of Fig. 3 and showing the wringer-rolls in an active position; and Fig. 3 is a plan view of the same, one of the wringer-rolls being shown in section.

To the inside of a pail A or like receptacle 30 is secured a frame B, having parallel side arms B' and B'', terminating in integral cross-bars B³ and B⁴, from which extend segmental ends B⁵ and B⁶, riveted or otherwise secured to the inside of the pail A, so as to securely hold the frame B in position in the upper end 35 of the pail and to render the frame exceedingly strong and durable. In the side arms B' and B'' are formed longitudinally-extending slots B⁷, in which are slidably journaled the ends of the shaft C' of a wringer-roll C, the ends of the shaft being pressed on by the 40 free ends of springs C², held on the side arms B' and B'' of the frame B. By the arrangement described the wringer-roll C is yieldingly mounted in the frame B and is normally 45 pressed toward a second wringer-roll D, mounted to rotate loosely on a shaft D', having one end provided with an angular offset forming a pivot D², mounted to swing in the cross-bar B⁴ of the frame B to allow of swinging the shaft D' and its wringer-roll D into an 50 open position, as shown in Fig. 1, to allow of

placing the mop in position on the wringer-roll C and to then permit swinging the wringer-roll D downward, so as to clamp the mop between the wringer-rolls C and D. 60

The free end of the shaft D' terminates in a handle D³, adapted to be taken hold of by the operator to permit of conveniently swinging the wringer-roll D into an open or closed position, as previously mentioned. The free 65 end of the shaft D' when swinging downward to bring the wringer-roll D into an active position passes over an incline B⁸, formed on the side arm B' to guide the free end of the shaft to the open bearing B⁹, formed in the upper 70 edge of the side arm B', which bearing B⁹ is inclined downwardly and outwardly to prevent accidental disengagement of the shaft D' from the said bearing. The side arm B² is also provided in its upper edge with an open 75 bearing B¹⁰ to receive the other end of the shaft D' when the latter is swung downward.

When the wringer-roll D is in an open position, as shown in Fig. 1, it is evident that the operator can conveniently place the mop on 80 the roll C, and then the wringer-roll D is swung downward to clamp the mop between the rolls C and D, the roll C then yielding sufficiently for the purpose, owing to the action of the springs C². The operator can now pull 85 the mop in an upward direction, so as to cause the wringer-rolls C and D to squeeze out the dirty water in the mop, and as the mop-wringer described forms a permanent fixture of the pail A and is located in the upper 90 portion thereof it is evident that the dirty water flows into the pail and is not liable to splash upon the floor during the wringing operation.

In order to conveniently hold the pail or 95 other receptacle A in position during the wringing operation, feet E are provided arranged on the outer lower portion of the pail and adapted to be stepped on by the operator during the wringing operation. 100

Having thus described my invention, I claim as new and desire to secure by Letters Patent—

1. A mop-wringer for pails, comprising a frame adapted to be secured to the pail, a wringer-roll yieldingly mounted in the said frame, a second wringer-roll, and a shaft on which the second wringer-roll is mounted to turn, the said shaft having one end provided with an integral offset extending approximately at right angles to the body of the shaft and forming a pivot mounted on the 110

said frame to permit of swinging the shaft and its wringer-roll upward into an open position, the frame being provided with open bearings to receive the said shaft when the latter is swung downward to bring the wringer-roll into active position.

2. A mop-wringer for pails, comprising a frame adapted to be secured to the pail, and having parallel side arms terminating in cross-bars extending outwardly from the side arms, a wringer-roll yieldingly mounted in the side arms, a shaft having one end provided with an angular offset forming a pivot mounted on one of said cross-bars to permit of swinging the shaft upward, and a second wringer-roll mounted to turn on the said shaft, the said side arms of the frame being provided in their upper edges with open bearings to receive the shaft of the second wringer-roll when the latter is in active position.

3. A mop-wringer for pails, comprising a frame adapted to be secured to the pail, a wringer-roll yieldingly mounted in the said frame, a shaft pivoted at one end on the said frame and provided at its other end with a handle, the handle end of the shaft being adapted to engage an incline on the said frame, to guide the handle end of the shaft to its bearing in the frame, and a second wringer-roll mounted to turn on the said shaft.

4. The combination with a pail, of a frame secured to the inside of the pail, a spring-pressed wringer-roll slidably journaled in the said frame, a second wringer-roll, and a shaft

for the second wringer-roll to turn on, the shaft being hinged at one end on the said frame and the other end of the shaft being formed into a handle, the said frame being provided with an open bearing inclined downwardly and outwardly, and adapted to receive the handle end of said shaft, the frame having a guide for directing the shaft into said bearing.

5. The combination with a pail, of a frame secured to the pail and having parallel side arms and integral cross-bars extending outwardly from the side arms, the side arms being provided with longitudinally-extending slots, a spring-pressed wringer-roll having the ends of its shaft slidably journaled in said slots, a second wringer-roll, a shaft on which the second wringer-roll is mounted to turn, the said shaft being hinged at one end to one of said cross-bars of the frame, and adapted to be swung upward into an open position, the side arms of the frame being provided in their upper edges with bearings to receive the shaft of said second wringer-roll, when the shaft is swung downward to bring the wringer-roll into active position.

In testimony whereof I have signed my name to this specification in the presence of two subscribing witnesses.

RASMUS CHRISTENSEN.
